US00D332943S

United States Patent [19]

Koiwa et al.

[11] Patent Number: Des. 332,943

[45] Date of Patent: ** Feb. 2, 1993

[54] IC CARD INPUT AND OUTPUT TERMINAL

[75] Inventors: Norimi Koiwa; Shigemi Sato, both of Tokyo, Japan

[73] Assignees: OKI Electric Industry Co., Ltd.; NTT Data Communications Systems Corporation, both of Tokyo, Japan

[**] Term: 14 Years

[21] Appl. No.: 525,023

[22] Filed: May 18, 1990

[30] Foreign Application Priority Data

Feb. 22, 1990 [JP] Japan 2-5369

[52] U.S. Cl. D14/105; D14/100

[57] CLAIM

The ornamental design for an IC card input/output terminal, as shown.

DESCRIPTION

FIG. 1 is a perspective view of an IC card input and output terminal showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
